UNITED STATES PATENT OFFICE

ALONZO G. DECKER, OF BALTIMORE COUNTY, MARYLAND, ASSIGNOR TO THE BLACK & DECKER MANUFACTURING COMPANY, OF TOWSON, MARYLAND, A CORPORATION OF MARYLAND

PORTABLE POWER DRIVEN PERCUSSIVE TOOL

Application filed April 29, 1931. Serial No. 533,612.

The invention relates to a portable power driven percussive tool or hammer of the reciprocating ram type. In the form in which this machine has been developed and reduced to practice it consists of a source of rotary motion as an electric motor or a flexible shaft, or this motion may be obtained from any other convenient source. The rotary motion is in turn converted by means of a crank or eccentric and a connecting rod into a reciprocating motion of a plunger or cross-head. By the conversion of rotary motion to reciprocating movement in this way a harmonic motion of the plunger or cross head results. It is, however, not essential that the reciprocating motion of the piston or plunger be harmonic, as the cross head may within the scope of the invention be reciprocated in any suitable and convenient manner.

The cross head is in turn mounted on and connected to the ram which it actuates and relatively to which the ram is adapted to have a reciprocating motion, the motion of the piston or plunger is communicated to the ram by and through certain resilient means, preferably in the form of one or more pneumatic members, which provide for a vibratory motion of the ram relatively to the plunger, the periodicity of which vibratory motion is determined by and is preferably a function of the rotative speed, the radius of the crank, the relative tension of the resilient members and the mass of the ram, it being understood that the unit comprising the ram and resilient members has a natural period of vibration or oscillation. In the present instance this natural period of vibration is in the preferred form of the hammer an integral factor of the speed of rotation of the crank so that there are one or two or more complete revolutions of the crank or other actuating member for each blow or stroke of the ram, whereby a speed of the ram may be obtained which is far in excess of that obtained from the crank alone.

In the operation of the tool embodying the invention in the preferred form the crank or any corresponding shaft from which the motion of the machine is obtained may have

a normal speed of from 1800 to 2,000 revolutions, this rotating motion being obtained from any suitable source. If an electric motor is employed, a motor operating at about 12,000 R. P. M. will be found satisfactory, the rotary speed being correspondingly reduced in transmission and it being understood that these figures are merely illustrative and are capable of wide variation. Under these circumstances, the speed of the ram would, where there are two complete revolutions of the crank to each blow, be 900 to 1,000 strokes per minute.

By thus designing and proportioning the apparatus the speed of the ram being a function of the tension and relative strength of the resilient members, the mass of the ram and the length of the stroke, the resilient members become a part of the actuating means whereby the motion of the crank, the momentum of the ram and the resilient thrust are combined to produce the vibration or stroke of the ram.

In the preferred form of hammer disclosed, the resilient members are each in the form of a pneumatic pad or flexible container filled with air or any other convenient gas and under pressure with suitable valve means whereby they may be further inflated to the desired pressure when and if at any time they become slightly deflated or the valve may be omitted and the pneumatic pads may be in the form of closed inflated containers on the order of a tennis ball which, after wearing out or becoming deflated, can be thrown away and replaced at a nominal cost.

In the accompanying drawings I have illustrated a reciprocating tool embodying the features of the invention in the preferred form.

In the drawings:

Figure 1 is an elevation of the tool, portions being broken away and shown in section.

Figure 2 is a fragmentary section at right angles to the plane of Figure 1 and on the line 2, 2.

Figure 3 is a section on the line 3, 3 transverse to the axis.

Figure 4 is a section on the line 4, 4 in Figure 2, representing a plane of the axis at right angles to the plane of Figure 2.

Figure 5 is a section on the line 5, 5 in Figure 4.

Figure 6 is a plan view with one of the pneumatic pads removed.

Figure 7 is a view showing the pad in the form of a ball.

Figure 8 is a view corresponding to Figure 4 showing a modified construction.

Figure 9 is a section on the line 9, 9 of Figure 8.

Figure 10 is a top plan view of one of the pads in the modified form, Figure 8.

Figure 11 is a side elevation of the same.

Referring to the drawings by numerals, each of which is used to indicate the same or similar parts in the different figures, the

20 machine illustrated in Figure 1 comprises a source of rotary motion for which purpose an electric motor 1 may be most conveniently utilized. This motor 1 is enclosed in a motor casing or housing 2, to which is

25 secured a suitable grip 3, and the construction also includes a gear casing 4 secured to the motor housing. A hammer barrel 5

secured to the gear casing 4 below the motor encloses the ram 6, which is mounted to re-

30 ciprocate in a suitable inner guiding cylinder or ram guide 7, which in the preferred form is spaced inwardly from the barrel 5 to reduce the transmission of heat to the

35 barrel and thereby to protect the hands of the operator.

The shaft 9 of the motor 1 carries a pinion 10, which meshes with a toothed gear 11 on the idler shaft 12, which carries a similar toothed gear 14 meshing in operation with

40 a larger toothed gear 15 on the crank shaft 16. The shafts 12 and 16 are mounted respectively in suitable bearings 17 and 18, supported in the gear casing 4.

The crank shaft 16, in turn, carries a crank disk 19 in which the crank pin 20 is eccentrically mounted. The crank pin is in turn engaged by a connecting rod 21 provided with a bearing 22 surrounding the crank pin. This connecting rod is in turn

45 secured at its lower end to the center of the cross bar 24 of a yoke 25, the connection being preferably of a conveniently disengageable type. In the form shown the transverse pin 26 is passed through a socket 27 on the

50 yoke and through the end of the connecting rod at 28 which is seated in the socket. This connection may, however, be made in any suitable manner.

In the form of hammer shown, in Figures

55 1 to 4, the side bars 30, 31 of the yoke are in the form of round rods or bolts threaded at one end into the cross bar 24 and reduced at their lower ends at 32, the reduced portions providing shoulders or abutments 33,

55 being passed through a cross head or plung-

er member 34 shown in the form of a transverse plate. The side bars 30, 31 of the yoke are secured below the plate by means of nuts 35 or in any suitable manner.

This cross head, plunger or piston 34, is

located within a suitable cavity 36 in the ram 6, which is closed at the top in any suitable manner as by means of a removable plate 37 held by screws 38.

Cross head 34 is supported within the ram 6 between pneumatic pads 39 below and 40 above, each of

75 which pads bears on one side against the crosshead or piston 34 which as best illustrated in Figure 2, is preferably shaped to conform to the pads.

The lower pad 39 bears on its opposite side against the bottom of the ram 6 which is also shaped to fit the pad, and the upper pad 40 bears at

80 its upper side against the cover or top plate 37, which is likewise shaped to fit the top of this pad 40.

The cross head, as shown, has ears or lugs 43 projecting into slots 42 in the sides of the cavity 36. The ears or lugs are engaged by the side bars 30 and 31,

85 as explained, and these side bars extend through holes 15 in the plate 37 into these slots 42.

Figure 6 shows the pad 40 removed. Pad 39 is identical with pad 40.

Figure 7 shows a spherical pad 41 which may be substituted for the pad 40, the spherical pad being probably capable of production at a smaller cost in large quantities.

Figures 8, 9 and 10 show a slightly different form of the invention in which the

100 yoke 50 having depending side bars 51 is secured to the cross head or plunger member 5 by means of journals 53 formed on the cross head or plunger 52, and seated in suitable journal bearings 54 in the side bars 51

105 of the yoke 50 near the lower ends. The ram 55 is chambered as in the previous instance to receive and enclose the cross head or plunger 52, and the ram is slotted at the

110 sides in the direction of its axis at 56. The cross head 52 has projecting ears 57 passing through the slots 56 in the ram parallel to the axis and terminating in journals 53 already described. These journals and the

115 side bars 51 occupy outer enlarged slots 51' in the outer surface of the ram. Within the chamber or cavity 58 in the ram are the pads 59 and 60 above and below the cross head 52, the respective pads bearing against

120 the corresponding sides of the cross head 52. The upper pad 59 also bears against a suitable cover 61 closing the cavity 58 in the ram at the top and suitably secured to the

125 top of the ram and the pad 60 bears at its lower side against the bottom of the ram.

The pads 59 and 60, illustrated in Figures 10 and 11, are shown as in the form of short cylinders, each having a centrally depressed portion on the top at 64 in which is

130 shown as located a suitable type of inflation.

valve 65 which may be closed by a screw cap 66 shown as square for convenient engagement with a socket wrench or in any suitable manner.

- 5 The hammer or percussive tool as shown in each instance is provided at its lower end with a tool bushing 68 in which a tool is intended to be inserted as best shown in Figure 4, the end of the tool shank projecting beyond the bushing as at 69 into the path of the ram.
- 10

In the operation of the tool the cable 13 being connected to a convenient source of electricity, and the current being controlled by means of a switch operated by the finger lever 13', the motor 1 is energized and controlled, started, stopped, etc.

The rotary motion of the motor is communicated by and through the gear train 20 10, 11, 12, 14, 15 to the crank shaft 16 and to the crank disk 19, carrying crank pin 20 whereby the rotary motion is communicated to the cross arm 24 of the yoke 25 and hence by way of the arms 30, 31 to the cross head 25 34, which in the preferred form of the invention shown is located within the central cavity 36, within the ram 6. Thus the reciprocating motion of the yoke is transmitted to the cross head 34 in the ram.

30 The pneumatic pads 40, 41 on each side of the cross head transfer the harmonic motion of the yoke and cross head modified by the resiliency of the pads to the ram, which is shown as chambered at 39' and 40' to fit the pads though this is not an absolutely essential provision.

As the ram is thus reciprocated by the motion of the cross head imparted thereto through the pads 39, 40, it is brought into 40 contact at the end of each stroke with the tool shank 69 projecting upwardly from the bushing 68.

The modified form, Figures 8, 9 and 10, has the same operation as that described, 45 the pad, Figures 10 and 11, being inflated when required by way of the valve 65, or the pads may be made as shown in Figures 6 and 7 without valves, to be thrown away when they have so deteriorated as to lack 50 the necessary resiliency.

It is of interest that the values or relative values of the resilient properties of the pads as compared with the mass of the ram may be so selected that the ram has a natural 55 period of vibration or oscillation which is equal to or an integral factor of the speed of rotation of the crank, i. e., the speed of the crank is a multiple of the speed of vibration of the ram. Preferably the ram makes 60 a single oscillation or stroke for each two or more complete revolutions of the crank though this element may be so selected as to give a stroke of the ram for each revolution of the crank. In this way the movements 65 or speed of the ram becomes greater than

that of the piston at the time of the impact, the action of the crank and the pads in applying the torque of the motor to the ram and converting it into the momentum of the ram, being cumulative resulting in the maximum impact in proportion to the weight of the tool and the size of the motor and the power consumed. The cushioning effect of the pads is also of importance in that it serves very efficiently to prevent the application of undue stress to the gear teeth, keys, shafts, etc. I have thus described specifically and in detail a portable hammer embodying the features of my invention in the preferred form in order that the nature, manner of operation and construction and using the same may be fully understood, however, the terms herein are used descriptively rather than in a limiting sense and the scope of the invention is defined in the claims.

What I claim as new and desire to secure by Letters Patent is: 1. The combination in a portable power driven percussive tool of a source of rotary motion, means for transforming rotary into reciprocating motion, a cross head reciprocated thereby, a ram, a pneumatic pad in the form of a gas inflated bag for transmitting the motion of the cross head to the ram, the ram being of heavy construction, having a central cavity, a plate closing the rear end of the cavity and means for securing the plate in position; a pad seat carried by the plate and a pad seat in the forward end of the ram, said seats being disposed toward the center of the ram, a yoke carrying the crosshead which is between the said seats and provided with corresponding seats on its opposite sides disposed toward said respective seats on the plate and ram, the pneumatic pads being located on each side of the cross head between and engaging the oppositely disposed seats of the crosshead and ram and plate, the plate being apertured to pass the yoke. 2. The combination in a portable power driven percussive tool of a source of reciprocating motion, a cross head to which said reciprocating motion is applied, a ram partially enclosing the cross head and adapted to reciprocate relatively thereto, a pneumatic pad in the form of a gas inflated bag on each side of the cross head in the direction of motion and between the cross head and the ram transmitting the reciprocating motion of the cross head to the ram, the cross head being provided with two seats for the respective bags for transmitting the thrust of the crosshead to the bags, the seats being disposed in the two opposite directions of reciprocation and the ram having corresponding seats engaging the bags from the sides opposite to those engaged by the cross head seats for transmitting to the ram

30

the thrust applied to the bags by the cross-head.

3. The combination in a portable power driven percussive tool of a source of rotary motion, a crank, a yoke and means connecting the crank to the yoke, a reciprocating ram, a guide therefor, the yoke having a crosshead partially enclosed by the ram which has two abutments spaced apart, one on each side of the cross head and a pneumatic pad in the form of a gas inflated bag on each side of the cross head between said cross head and the adjacent abutment whereby the motion of the cross head is communicated to the ram in a form modified by the yielding of the pneumatic element, the cross head being provided with two seats for the respective bags for transmitting the thrust of the crosshead to the bags, the seats being disposed in the two opposite directions of reciprocation and the ram having corresponding seats engaging the bags from the sides opposite to those engaged by the cross head seats for transmitting to the ram the thrust applied to the bags by the crosshead.

4. The combination in a portable power driven percussion tool of a barrel, a hollow cylindrical ram slotted at the sides mounted to reciprocate in the direction of the length of the barrel, a source of rotary motion, a crank, a yoke operated thereby, the yoke having a cross head mounted to reciprocate in the hollow of the ram, said ram being slotted at the sides to accommodate the yoke, the cross head having means extending through the slots into engagement with the yoke, and resilient means in the form of a gas inflated bag between the cross head and the ram on each side of the cross head in the direction of reciprocation.

5. The combination in a portable power driven percussive tool of a barrel, a hollow cylindrical ram slotted at the sides mounted to reciprocate in the direction of the length of the barrel, a source of rotary motion, a crank operated thereby, a yoke having a cross head mounted to reciprocate in the hollow of the ram, said ram being slotted at the sides to accommodate the yoke, the cross head having means extending through the slots into engagement with the yoke, said means on the cross head having journals projecting therefrom and the yoke having corresponding journal bearings to receive the same, and a pneumatic pad between the cross head and the ram on each side of the cross head in the direction of reciprocation.

Signed by me at Towson, Baltimore County, Maryland, this 18th day of April, 1931.

ALONZO G. DECKER.
